UNITED STATES PATENT OFFICE.

EDWARD KRONMAN, OF NEW YORK, N. Y.

DESIGN FOR A STERILIZER.

Application filed September 29, 1925. Serial No. 14,939. Term of patent 14 years.

To all whom it may concern:

Be it known that I, EDWARD KRONMAN, a citizen of the United States, residing in the borough of Manhattan, city, county, and State of New York, have invented a new, original, and ornamental Design for Sterilizer, of which the following is a specification, reference being had to the accompanying drawing, forming part thereof.

The figure is a perspective view of a sterilizer, showing my new design.

I claim:—

The ornamental design for a sterilizer, as shown.

EDWARD KRONMAN.
